(57) **CLAIM**

I claim the ornamental design for an awning, as shown and described.

DESCRIPTION

FIG. 1 is a perspective view of my design shown in an operational environment;

FIG. 2 is a frontal view of the design of FIG. 1;

FIG. 3 is a right-hand lateral view of the design of FIG. 1,

the opposite lateral view being identical thereto;

FIG. 4 is a top view of the design of FIG. 1;

FIG. 5 is a bottom view of the design of FIG. 1; and,

FIG. 6 is a rear view of the design of FIG. 1.

The broken line structure that is shown in FIGS. 1–6 is for illustrative purposes only, and forms no part of the claimed design.
